A. FERNANDEZ.
SMOKE HANDLING APPARATUS.
APPLICATION FILED SEPT. 20, 1916.

1,232,669.

Patented July 10, 1917.

UNITED STATES PATENT OFFICE.

ALPHONSE FERNANDEZ, OF WASHINGTON, DISTRICT OF COLUMBIA.

SMOKE-HANDLING APPARATUS.

1,232,669.

Specification of Letters Patent. Patented July 10, 1917.

Application filed September 20, 1916. Serial No. 121,250.

To all whom it may concern:

Be it known that I, ALPHONSE FERNANDEZ, a subject of the King of Spain, residing at the city of Washington, in the District of Columbia, have invented certain new and useful Improvements in Smoke-Handling Apparatus; and I do declare the following to be a full, clear, and exact description of the invention, such as will enable others skilled in the art to which it appertains to make and use the same.

The present invention is designed primarily for collecting the smoke from the furnaces or exhaust gases from the engines of submarines while submerged and expelling it or them at intervals under pressure, but it is to be understood that the device is applicable for instance, to locomotives when traveling through towns in which excessive smoke is not permitted, and that it may in fact be employed wherever applicable.

The object of the device is to provide simple and efficient means for the attainment of the above named results, considerable difficulty having been heretofore encountered in the proper expulsion of the smoke from the furnaces and exhaust gases from the engines of submarines when the latter are submerged with their smoke stacks folded or collapsed.

With the foregoing general object in view, the invention resides in certain novel features of construction and in unique combinations of parts to be hereinafter fully described and claimed, the descriptive matter being supplemented by the accompanying drawing which constitutes a part of this application and in which a sectional view of the improved apparatus is shown.

In this drawing the numeral 1 designates a furnace and 2 has reference to the outlet pipe which is adapted to lead to a suitable smoke stack, said pipe having a branch 3 and having above said branch a damper or valve 4, the branch 3 being also provided with a valve as indicated at 5. Auxiliary branches 6 lead from the end of the branch 3 to inlet ports 7 in the opposite ends of a pump cylinder 8, said ends also having outlet ports 9. Through suitable pipes 10 the two exhaust ports 9 discharge into the lower end of a cylindrical smoke collecting chamber 11, a check valve 12 being located at the inlet of said chamber. The chamber 11 is provided with an outlet pipe 13 having a cut off valve 14 and at its outer end an outwardly opening check valve 15 which may

discharge through the shell 16 of a submarine when the invention is applied to the latter. A pressure gage 17 is also provided for the chamber 12 as shown.

A screw 18 extends longitudinally through the pump cylinder 8 and is shown in the present embodiment of the invention as being provided with a gear 19 on one end by means of which any suitable operating mechanism not shown may be applied to turn said screw, the latter being threaded through a piston 20 in the cylinder 8. The piston 20 is formed with an opening 21 through which a valve shifting rod 22 passes, the opposite ends of said rod passing through the ends of the cylinder and being connected to cross heads 23 having slide valves 24 at their ends for controlling the ports 7 and 9. Near its opposite ends the rod 22 is provided with abutments 25 disposed within the cylinder to be struck by the piston 20 as the latter moves to the opposite ends of the cylinder during its reciprocation, it being understood that the operating means above referred to is adapted to alternately drive the screw 18 in opposite directions.

During the downward travel of the piston 20 the uppermost inlet 7 is open and the upper exhaust port 9 is closed while the positions of the lower valves are reversed so that the piston will force any smoke within the lower end of the cylinder 8 through the check valve 12 into the collecting chamber 11. The piston 20 in thus traveling downward strikes the lower abutment 25 and thus shifts the rod 22 so as to move both cross heads 23 to reverse the positions of the valves 24. As piston 20 now rises, smoke is taken into the lower end of the cylinder 8 and expelled from the upper end thereof and when said piston comes in contact with the upper abutment, the valves will be again reversed. The pump acting in this manner draws the smoke from the furnace 1 and deposits it into the collecting chamber 11 when the valves 4 and 5 are respectively closed and open.

Within the chamber 11 is a smoke expelling piston 26 operated by means of a screw 27 having at its upper end a gear or the like 28 by means of which power may be applied to cause the piston to move downward quickly when the attendant observes by the pressure gage 17 that a predetermined amount of smoke pressure exists in the

chamber 11. The descent of piston 26 obviously forces the smoke through the valves 14 and 15 and the pipe 13 and if the device be used on a submarine, said valve 15 prevents any water from entering the apparatus.

The valve 14 is merely used as a safety device to prevent the entrance of water into the apparatus in case the valve 15 should not operate properly, and similarly, if through any accident water should enter the chamber 11 and the check valve 12 would not operate to prevent the passage of such water into the pump, a cut off valve 29 in one of the pipes 10 may be closed by hand.

By constructing the apparatus in the manner shown and described or in approximately this way, it will be highly efficient and durable and as above stated is particularly applicable for use on submarines although it may well be employed wherever desirable.

In the drawings I have shown a number of specific details of construction for illustrative purposes and have herein described such details but it is to be understood that within the scope of the invention as claimed, numerous changes may be made without sacrificing the principal advantages.

It is to be understood that the improved apparatus is not restricted to the handling of smoke since it may well be employed for expelling the exhaust gases of internal combustion engines.

I claim:

1. A smoke or gas handling apparatus for use in connection with furnaces and other gas expelling apparatuses comprising a smoke or gas collecting chamber, a pump for forcing the smoke or gas into said chamber, and means for forcing the collected smoke or gas from said chamber.

2. A smoke or gas handling apparatus for use in connection with furnaces and other gas expelling apparatuses comprising a smoke or gas collecting chamber having therein a piston, a pump for forcing the

smoke or gas into said chamber in advance of the piston, and means for projecting said piston to expel the collected smoke or gas.

3. A smoke or gas handling apparatus for use in connection with furnaces and other gas expelling apparatuses comprising a collecting chamber, a cylinder having therein a piston, smoke or gas inlets into the opposite ends of the cylinder, smoke or gas outlets from said ends into the collecting chamber, valves for said inlets and outlets, means for reciprocating said piston to force the smoke or gas into the collecting chamber, and means for forcing the collected smoke or gas from said chamber.

4. A smoke or gas handling apparatus for use in connection with furnaces and other gas expelling apparatuses comprising a pump cylinder having therein a piston, a screw for reciprocating said piston, smoke or gas inlets from the furnace into the opposite ends of the cylinder, a cylindrical smoke or gas collecting chamber, smoke or gas outlets from the ends of the cylinder into said chamber, valves for said inlets and outlets, a check valve for the inlet of said collecting chamber, an outlet from said collecting chamber, a check valve for this outlet, a smoke or gas expelling piston in the collecting chamber, and a screw for operating this piston.

5. The method of handling smoke from a furnace or other gas expelling apparatus consisting in pumping said smoke or gases into a collecting chamber until the pressure in the latter reaches a predetermined degree, and in then forcing the smoke or gas from said chamber.

In testimony whereof I have hereunto set my hand in the presence of two subscribing witnesses.

ALPHONSE FERNANDEZ.
